UNITED STATES PATENT OFFICE

2,438,289

BEET HARVESTING MACHINE

Lawrence Barayuga Karaang, Santa Maria, Calif.

Application September 8, 1943, Serial No. 501,525

1 Claim. (Cl. 55—107)

1

This invention relates to beet harvesting machines.

An object of this invention is to provide a machine of the character described, having highly improved means for cutting off the tops of the beets, and also for digging up the beets and harvesting them.

A further object of this invention is to provide a machine of the character described, having a plow to slice the ground and avoid big clogs, the plow being designed to go deep into the ground and loosen up the earth to facilitate digging up the beets.

A further object of this invention is to provide in a machine of the character described, means to cut off the tops of the beets where the beets are high above the ground or substantially at the ground level.

Yet a further object of this invention is to provide in a machine of the character described, conveyors to take the cut off tops of the beets and also the dug up beets to suitable receptacles or wagons.

Still another object of this invention is to provide in a machine of the character described, a digger for digging up the beets and improved means for adjusting the level of the digger, and said machine also including means to bring the dug up beets onto the conveyor.

Yet another object of this invention is to provide a compact and durable machine of the character described, which shall be practical and efficient to a high degree in use.

Other objects of this invention will in part be obvious and in part hereinafter pointed out.

The invention accordingly consists in the features of construction, combinations of elements, and arrangement of parts which will be exemplified in the construction hereinafter described, and of which the scope of application will be indicated in the following claim.

In the accompanying drawing, in which is shown various possible illustrative embodiments of this invention,

Fig. 1 is a side elevational view of a machine embodying the invention;

Fig. 2 is a front end view of the machine;

Fig. 3 is a rear end view of the machine;

Fig. 4 is a vertical, cross-sectional view through the body of the machine;

Fig. 5 is an elevational, cross-sectional view illustrating a part of the machine;

Fig. 6 is a cross-sectional view taken on line 6—6 of Fig. 5;

Fig. 7 is a cross-sectional view taken on line 7—7 of Fig. 5; and

Fig. 8 is an end view of the structure shown in Fig. 5.

Referring now in detail to the drawing, 10 designates a machine embodying the invention. 60

2

The same comprises a horizontal frame 11 supported on front wheels 12 and rear wheels 13. On frame 11 is a second frame 14 shown in Fig. 5. On frame 14 is supported a rotary shaft 15 which may be driven through a universal joint connection with shaft 16 obtaining power in any suitable manner (not shown).

On shaft 15 is a gear 17. On frame 14 and above shaft 15 is a shaft 18. On shaft 18 is a gear 19 meshing with gear 17. On said shaft is another gear 20. Journalled in the frame 14 and above shaft 18 is another shaft 21 carrying a gear 22 meshing with gear 20. On shaft 21 is a bevel gear 23.

Also journalled in frame 14 are a pair of parallel horizontal shafts 25, 25a extending rearwardly of said frame. At the rear ends of shafts 25, 25a are bevel gears 26. The shaft 25 carries a sprocket gear 27 which is engaged by the endless chain 28, which also engages the smaller sprocket gear 29, on the shaft 21. The shaft 25a carries a sprocket gear 27a, which is engaged by the endless chain 28a, which also engages the smaller sprocket gear 29a, on the shaft 18, which is located immediately below the shaft 21.

At the rear end of frame 11 is a vertical frame 30 (see Figs. 3 and 5). Carried by frame 30 is a transverse shaft 31 loosely carrying bevel gears 32 meshing with the bevel gears 26.

Shafts 25, 25a carry sprocket wheels 34 connected by sprocket chains 35 to sprocket wheels 36 carried on a pair of horizontal shafts 37, 37a located below the shafts 25, 25a. On shaft 37a is a sprocket wheel 37b connected by sprocket chain 37c to a sprocket wheel 37d on a shaft 37e supported by the frame. On said frame is a second shaft 37f. On shafts 37, 37e and 37f are rollers 37g carrying a belt 40. Connected to the front ends of shafts 37, 37a by universal joints 43 are downwardly and forwardly inclined rods 44 connected by universal joints 45 to conical screw-like members 46 adapted to carry the dug up beets as will appear hereinafter onto a conveyor to be described later.

On shaft 25a is a sprocket wheel 50 connected by sprocket chain 51 to a sprocket wheel 52 on a shaft 53 suitably journalled in the frame and disposed parallel to shaft 25a. On the sprocket wheel 52 are sprocket chains 55 for the purpose hereinafter appearing.

Fixed to the body of the machine is an upwardly and outwardly inclined chute 56. The upper end of the chute supports a shaft 57 on which there are mounted sprocket wheels 58. Carried by the sprocket wheels 58, 55 is a conveyor 60 adapted to move the dug up beets from the conveyor 40 upwardly within chute 56 to dump them on a wagon or any other suitable receptacle.

On the frame of the machine is a shaft 70

carrying a sprocket wheel 71. On said frame is also an idler sprocket wheel 72. Fixed to one of the bevel gears 32 for rotation therewith is a sprocket wheel 80. On the frame are upstanding arms 82. Supported by the arms 82 is a shaft 83. On shaft 83 is a sprocket wheel 84. Extending over the sprocket wheel 80 and around sprocket wheels 71 and 84 is a sprocket chain 85 passing beneath and engaging the idler sprocket wheel 82. Thus rotation of the bevel gear 32 will rotate shaft 83. Fixed to the machine is a downwardly inclined chute 90. At the lower end of the chute is a horizontal shaft 91. On shaft 91 are sprocket wheels 92. On shaft 83 are sprocket wheels 93. Extending over the sprocket wheels 92, 93 is a sprocket type conveyor 95 adapted to carry cut-off beet tops up the chute 90. At the upper end of chute 90 is a rearwardly and downwardly inclined chute 96 to dump the beet tops into a wagon or receptacle.

On shaft 70 are sprocket wheels 97. On the frame is a shaft 98 disposed forwardly of and at a lower level than the shaft 70. On shaft 70 is a sprocket wheel 100. On shaft 98 is a sprocket wheel 101. Over said sprocket wheels is a sprocket chain type conveyor 102. Below said conveyor is a chute 103. The screw members 46 serve to carry the dug up beets onto the chute 103. The conveyor has fingers to move the beet up the chute 103 and onto belt 40 where it is carried onto the chute 56.

Means is provided for digging up the beets. To this end there is fixed to the frame 11 a fixed digging plow or digger 110. Adjustable digging means is also provided for digging up the beets.

To this end there is slidably mounted on frame 11 a digger 111 having a vertical standard 111b. The digger 111 is held in position by a sliding guide 112. Pivoted to the frame 11 as at 113 is a lever 114. The lever 114 is pivoted to the upper end of the digger 111 as at 115. Pivoted to the upper end of lever 114 is a link 116, the upper end of which is pivoted to the horizontal beam 116a, and this beam is engaged by the projection 121a, on the worm gear 120.

By the rotation of the worm gear 120, by operating the worm 121, the projection 121a will raise the beam 116a, thus lifting the link 116 and swinging the lever 114, which lifts the plow 111.

Worm 121 is on the frame and is provided with a handle 122 for rotating the worm wheel.

The lower end of the conical separator or member 46 has a bearing at 111a on the heel of the plow or digger 111.

Means is provided to cut off the tops of the beets. To this end there is mounted in the frame 14 a vertical shaft 130. Carried by the shaft 130 is a bevel gear 131 meshing with the bevel gear 23 on the shaft 21. Bevel gear 131 is connected through suitable sprocket wheels and chains to a pair of vertical shafts 135. At the lower end of shafts 135 are rotary cutters 136 disposed above the level of the ground and adapted to cut off the beet tops.

The shafts 135 are splined to the sprocket wheels which are mounted thereon. The upper end of the shafts 135 are journaled in bearings 136. Bearings 136 are connected by universal joints 137 to members 138 having curved upper portions and downwardly extending vertical portions 139.

Pivoted to the lower ends of members 139 are free level slides 140. These slides slide over the beet tops and press the tops downward.

On members 139 are stop pins 141. On said pins are compression springs 142 abutting at their upper ends fixed stops 144 and at their lower end the stop pins 141. The springs 142 thus urge members 138 downwardly.

The slide 140 is connected to an upright bar 151, the upper end of which is pivoted to the end of the beam 156, which is again pivoted at 157 upon a stationary arm 161a, fixed on the horizontal bar or rod 161, which is fixed to the frame. A plurality of weights 158 are supported on the outer end of the beam 156, and by these weights the pressure of the slide 140 is balanced, or modified.

It will be understood that the slide 140, levers 151, 156, and weight 158 are duplicated as there are two sets side by side as shown in Fig. 2 of the drawing.

A vertical rod 160 is pivotally connected at its lower end to the slide 140, and slides through the bar or rod 161 at its upper end.

A plow 171 is supported on the upwardly curved member 170, which is provided with a vertical arm 170a, which slides vertically through the bar 161. On the upper end of this vertical arm 170a a cross pin 170b extends through the arm 170a and engages the bar 161 and prevents the plow from dropping. A lever bar 175 is pivoted at one end to the vertical bar 170a and has pivotal connection at the other end with the standard of the plow 110.

It will thus be seen that there is provided a device in which the several objects of this invention are achieved, and which is well adapted to meet the conditions of practical use.

As various possible embodiments might be made of the above invention, and as various changes might be made in the embodiments above set forth, it is to be understood that all matter herein set forth or shown in the accompanying drawing is to be interpreted as illustrative and not in a limiting sense.

Having thus described my invention, I claim as new and desire to secure by Letters Patent:

45 A beet harvester consisting of a member adapted to slide over the tops of beets to press them downwardly, a weighted beam having connection with said member to vary its pressure on the beet tops, a conveyor for removing severed beet tops, a rotary cutter arranged between the lower end of the conveyor and the member, means for rotating the cutter, and a spring having connection with the member and the cutter to hold the same downwardly.
